J. W. ELLS.
 GAS AND AIR HEATING APPARATUS FOR METALLURGIC FURNACES.
 No. 105,558. Patented July 19, 1870.

United States Patent Office.

JOSIAH W. ELLS, OF PITTSBURG, PENNSYLVANIA, ASSIGNOR TO HIMSELF
AND S. M. KIER, OF SAME PLACE.

Letters Patent No. 105,558, dated July 19, 1870; antedated July 6, 1870.

IMPROVEMENT IN GAS AND AIR-HEATING APPARATUS FOR METALLURGIC FURNACES.

The Schedule referred to in these Letters Patent and making part of the same

To all whom it may concern:

Be it known that I, JOSIAH W. ELLS, of Pittsburgh, in the county of Allegheny and State of Pennsylvania, have invented a new and useful Improvement in Gas and Air-heating Apparatus, such as may be applied to furnaces of various kinds, and for various purposes. In this apparatus the gases and air are heated and expanded on their way to the place designated for their joint combustion by being directed through tubes brought to a white heat by the escaping products of said combustion playing around the outside of them on its way to the chimney.

The nature of my invention consists in so arranging the gas and air-tubes within the space of the heating-chamber, in combination with air and gas-passages at opposite ends of said chamber, and with a properly-constructed and operating damper, as that the gas will be directed through one set of tubes, while the air passes through the other set, or *vice versa*, at the option of the furnace-man, or the person having it in charge.

Also, so arranging the gas and air-supplying tubes, with their respective passages, at each end of the heating-chamber, damper-chest, and inlet-ports, that, by changing the position of the damper so as to close one port and open the other, the current of gases, as they pass into the furnace, will be made to enter either above or below the current of air, as the circumstances of the case may require.

Also, in so arranging the damper and damper-chest, with its ports, in connection with the inlet, air, and gas-passages, as that a greater portion of the under side of said damper will always be exposed to the cooling influence of the atmosphere, and thereby less liable to become overheated.

To enable others skilled in the art of furnace building, to understand, make, and use my invention, I will proceed to describe its construction and operation by reference to the accompanying drawing, in which—

Figure 1 represents a front elevation of my improved apparatus, one of the doors being open, exposing the tubes on that side.

Figure 2 represents a transverse vertical section of the same, showing both clusters of tubes, damper-chest, and damper therein.

Figure 3 represents a longitudinal transverse section of the entire apparatus, on a horizontal plane, above the upper range of tubes.

Figure 4 is a transverse vertical section of the rear gas and air-passage and combustion-chamber or furnace.

Figure 5 represents a section, on a horizontal plane, of the damper-chest.

Figure 6, vertical transverse section of the same.

All the drawings are lettered, and similar letters denote like parts in the several views.

I construct my apparatus by making a long, close, covered chamber, A, across which extend two partitions, B' and B", leaving a space between them and the outside walls, each of which is divided by a middle wall, C' and C", so as to form, at both ends of said chamber, a gas and air-passage.

The passages, J' J", at the front end are open to the atmosphere, while those, K' K", at the rear or opposite end of the chamber A lead, by suitable channels, E' E", one above the other, into the furnace F.

Through the body of the chamber A and transverse partitions B' B", so that the front air and gas-passages J' J" shall communicate with those, K' K", at the opposite end of the chamber, is placed a series of highly refractory or heat-sustaining tubes, H M.

Just above the air and gas-passages J' J", at the front end of the chamber A, is placed a damper-chest, S, through the bottom of which are two openings or ports, T' T", each leading downward into the gas and air-passage immediately beneath.

Inside of this chest S is a sliding gas-valve or damper, V, large enough to cover one port, and is provided with a handle, m, that protrudes through the outside wall, by which it may be shifted or moved so as to close or open either port.

For the entrance of the gases, the damper-chest S is furnished with an inlet-pipe, W, so arranged as to convey the gases into it directly above the valve V, but it may be contrived to enter them at any other convenient point.

The inflammable gases which are to be used may be generated by the slow combustion of carbonaceous fuel in an apparatus constructed for that purpose. These gases, however generated, are conveyed into the damper-chest S through the pipe W, and, if the operations of the furnace require that these gases shall enter it below the air-current, the door, D', of the passage-way J" on that side of the chamber is to be closed, and the damper V shifted so as to open the port, T', leading into that passage-way, which operation or movement of the damper shuts the port, T", of the adjoining passage-way J, the door D' of which is then to be opened. The gases will now descend through the open port into the passage-way in communication with the damper-chest S, and pass through the tubes M into the passage-way, K", at the rear end of said tubes, and from thence, by a continuation of this passage-way or channel E", direct into the furnace F. The air, entering the open door D', will pass in like manner through the tubes, H, at that side of the chamber A into its passage-way, K, at the opposite end, and through a channel, E, into the furnace above the gas-current, where the two currents will unite, and are to be fired.

The heated volatile products, or spent gases resulting from the combustion of the said currents of gas

and air, will flow out of the furnace F, and into and down a drop-flue, N, and, by a continuation of said flue under the sole of the basin in the direction indicated by the dotted lines drawn diagonally across the furnace, through a channel in the wall of the chamber A, and, after circulating around the outside of the tubes H M, will eventually enter and escape by the chimney P.

Should the tubes M, through which the inflammable gases are supposed to be passing, become choked by a deposit of soot or other forms of carbonaceous matter requiring a supply of oxygen or air to assist in burning it out, or should it be desirable to have the current of air, as it enters the furnace, pass under the current of gas instead of over it, then, and in that case, the door D', open for the admission of air, is to be closed, and the valve or damper V changed or moved from the port, T", it previously covered, so as to open that, and close the other port, T'. The gases will, by this means, be cut off from those tubes they formerly passed through, and be directed into and through those before used as air-supplying tubes, and its channels into the furnace. Now, on opening the door, D", of that passage-way, J', formerly occupied by the ingoing gases, air will be admitted to those tubes and passages, which, by coming in contact with the carbonaceous matter deposited therein, such is the affinity of oxygen for carbon at a high heat that it is soon burned out, leaving the tubes as clear as before, while the current of air, as it enters the furnace F, will pass under the current of gas, and both objects be effectuated.

The air, as it enters the open passage-way, operates against the under side of the damper V, and keeps it comparatively cool.

Having stated the nature of my invention,

I claim—

1. Arranging the gas and air-supplying tubes in such a manner, and in combination with the air and gas-passages at opposite ends of a heating-chamber, that, with a properly-constructed and operating valve or damper, the gas will be directed through one set of tubes, while the air is passing through the other set, or *vice versa*, at the option of the furnace-man, or the person having it in charge, substantially in the manner and for the purposes herein set forth.

2. So arranging the gas and air-supplying tubes, with their respective passages, at each end of the heating-chamber, damper-chest, and inlet-ports, that, by changing the position of the damper so as to close one port and open the other, the current of gases, as they pass into the furnace, will be made to enter either above or below the current of ingoing air, as the circumstances of the case may require.

3. So arranging the damper and damper-chest, with its ports, in connection with the inlet, air, and gas-passages, as that a portion of the damper will be exposed to the cooling influence of the atmosphere, in the manner and for the purposes herein set forth.

JOSIAH W. ELLS.
